UNITED STATES PATENT OFFICE.

WILLIAM C. STUCKEL, OF CHICAGO, ILLINOIS.

WATER-TUBE BOILER.

SPECIFICATION forming part of Letters Patent No. 585,487, dated June 29, 1897.

Application filed December 12, 1896. Serial No. 615,491. (No model.)

To all whom it may concern:

Be it known that I, WILLIAM C. STUCKEL, of Chicago, in the county of Cook and State of Illinois, have invented a new and Improved 5 Water-Tube Boiler, of which the following is a full, clear, and exact description.

The object of the invention is to provide a new and improved water-tube boiler which is simple and durable in construction and arranged to insure complete combustion of the fuel, a rapid circulation of the water, and a consequent quick generation of the steam.

The invention consists principally of an upper and a lower water-compartment, a series of inner upflow water-tubes connecting the compartments, a series of outer downflow water-tubes surrounding the said inner tubes, and a fire-box in the said lower water-compartment and having its crown-sheet extending below the said inward upflow water-tubes to cause the heated water to rise directly to the upflow-tubes, the cold water flowing downward from the said outer downflow-tubes to the crown-sheet.

25 The invention also consists of certain parts and details and combinations of the same, as will be fully described hereinafter and then pointed out in the claims.

Reference is to be had to the accompanying 30 drawings, forming a part of this specification, in which similar characters of reference indicate corresponding parts in all the figures.

Figure 1 is a sectional side elevation of the improvement. Fig. 2 is a sectional plan view 35 of the same on the line 2 2 of Fig. 1, and Fig. 3 is a similar view of the same on the line 3 3 of Fig. 1.

The improved boiler is provided with shells A A', having flue-sheets B and B', located 40 one above the other, to form with the shells the lower water-compartment C and the upper water-compartment C'. In the lower water-compartment C is arranged a fire-box D, the shell D' of which extends a suitable distance inward from the shell A of the water-compartment C, so that a circular water-leg is formed, as indicated in Fig. 1. The crown-sheet D² of the fire-box D carries a lower smoke-flue D³, connected with the flue-sheet 45 B and in vertical alinement with a smoke-flue E, extending from the flue-sheet B' through the compartment C' and the top sheet thereof.

A series of water-tubes F connect the sheets B and B', and the said tubes are arranged in circular rows, of which the inner row forms 55 a space in alinement with the smoke-flues D³ and E, as will be readily understood by reference to the drawings. The tubes F are of comparatively small diameter and are arranged with their lower ends directly over 60 the crown-sheet D², so that the water coming in contact with the crown-sheet and being heated thereby is caused to rise directly to the lower ends of the said tubes F, to pass through the same in an upward direction and 65 finally reach the upper compartment C'.

A series of downflow water-tubes G is arranged in a circle outside the outermost row of tubes F, so as to surround the same, as is plainly indicated in Figs. 2 and 3, the said 70 tubes G being likewise attached to the flue-sheets B and B' and serving to carry the cooler water downward from the compartment C' to the lower compartment C to establish a complete circulation.

75 It is evident that the lower ends of the larger tubes G are out of the influence of the heat emanating from the crown-sheet B³, so that the cooler water will readily flow down the said tubes G to the crown-sheet and water-leg of the compartment C to be heated, so as to rise directly to the inner tubes F, as above described. A mantle of asbestos or the like incloses the downflow water-tubes G and extends between the flue-sheets B and B', as 80 plainly shown in the drawings.

The smoke and gases rising from the fire-box D through the flue D³ are caused to pass between the several tubes F and G by a cone-shaped deflector H, suspended in the space 90 formed by the innermost row of tubes F, the said deflector being located directly above the upper end of the flue D³, as is plainly indicated in Fig. 1. The deflector H, preferably made of fire-brick, is supported by a link I 95 from a cone-shaped cast-iron deflector J, arranged a short distance below the lower end of the smoke-flue E in the space formed by the innermost row of tubes F. This deflector J is carried by rods K, held on lugs K', riveted to the flue E.

100 It is evident that by the arrangement of deflectors the upward flow of the smoke is retarded to cause a burning of the smoke and

gases in the upper part of the fire-box D and flue D³, so as to insure complete combustion and at the same time render the boiler comparatively smokeless.

5 The rising gases are deflected outwardly among the tubes F and G by the lower deflector H, and a similar deflection is caused by the upper deflector J, it being understood that the gases in rising tend to pass to the center space to reach the flue E and in doing so strike the uppermost deflector J to be again spread outward and distributed among the tubes F and G. The gases finally pass under the flue-sheet B' to the center space above the deflector J to rise in the flue E to the outside.

10 The downflow water-tubes G have a larger area than the aggregate area of all the upflow-tubes F, so that an unobstructed circulation of the water is had at all times.

15 Having thus fully described my invention, I claim as new and desire to secure by Letters Patent—

1. A steam-boiler having a shell, a fire-box at the bottom of the shell, a flue passing from the fire-box upwardly and centrally into the shell, a flue-sheet located horizontally within the shell, and having a central orifice at the edges of which the upper end of the flue is connected, a second flue-sheet disposed horizontally within the shell and above the first flue-sheet, a series of downflow water-tubes extending between the flue-sheets and located in a circular line adjacent to the sides of the shell, a series of upflow water-tubes extending between the flue-sheets and located inward from the downflow-tubes, the upflow-tubes being smaller than the downflow-tubes and being disposed to leave a central passage within the boiler and in vertical alinement with the flue of the fire-box, a second flue extending upward from the central orifice in the upper flue-sheet and running centrally through the boiler to the upper end thereof, and two deflector-plates located within the central passage formed by the downflow water-tubes, one of said deflector-plates being

suspended from the uppermost flue and the second of said deflector-plates being suspended from the first-named deflector-plate, substantially as described.

2. A boiler having a shell, a fire-box at the lower portion of the shell, a flue running upward from the fire-box, a flue-sheet disposed horizontally within the shell and having a central orifice to the edges of which the upper end of the flue is connected, a second flue-sheet located above the first flue-sheet and arranged horizontally within the shell, a series of water-tubes passing between the flue-sheets and disposed to leave a central passage vertically alined with the flue, a second flue extending upward from the second flue-sheet and having its lower end connected with the edges of a centrally-disposed orifice in the second-named flue-sheet, and a deflector-plate held within the passage formed by the water-tubes whereby to throw the draft outward between the tubes, substantially as described.

3. A steam-boiler having an exterior shell or casing, a fire-box at the lower portion of the shell or casing, a flue passing upwardly from the fire-box, a flue-sheet disposed horizontally within the shell or casing and having an orifice through which the flue communicates, a second flue-sheet located horizontally within the shell or casing and above the first flue-sheet, a series of tubes passing between the flue-sheets and communicating with the space respectively above and below the flue-sheets, a second flue passing upwardly from an orifice within the second flue-sheet and leading out of the flue or casing, the two flues being in alinement with each other, and a deflector hung within the space between the two flues and between the two flue-sheets whereby to throw the draft from the fire-box outward between the tubes, substantially as described.

WILLIAM C. STUCKEL.
